WINDOW CONSTRUCTION

William Stuckey, Kankakee, Ill.

Application April 26, 1957, Serial No. 655,230

5 Claims. (Cl. 20—52.1)

This invention relates to windows, and more particularly to a window of the type wherein no sash frames are employed.

A main object of the invention is to provide an improved window of the sashless type, said window being simple in construction, being easy to install, and being attractive in appearance.

A further object of the invention is to provide an improved window of the sash less type which involves inexpensive components, which is durable in construction, which is easy to open and close, and which is highly effective in excluding rain, cold air, dust, or other undesirable substances in the atmosphere.

Further objects and advantages of the invention will become apparent from the following description and claims, and from the accompanying drawings, wherein:

Figure 1 is a perspective view of an improved sashless window constructed in accordance with the present invention.

Figure 2 is a perspective view of the components of the window of Figure 1, shown in separated positions.

Figure 3 is an enlarged vertical cross sectional view taken on line 3—3 of Figure 1.

Figure 4 is a vertical cross sectional view, similar to Figure 3, but showing the lower window pane element in an elevated position.

Figure 5 is a fragmentary horizontal cross sectional view taken on line 5—5 of Figure 3.

Figure 6 is a fragmentary horizontal cross sectional view taken on line 6—6 of Figure 3.

Referring to the drawings, 11 generally designates a double window frame containing a pair of side-by-side windows according to the present invention. The window frame 11 comprises the horizontal head jamb 12 secured to the outside vertical jamb members 13 and the intermediate vertical jamb member 14. The frame 11 also comprises the horizontal bottom sill member 15.

Each of the window units provided in the frame 11 is substantially identical. Thus, the window unit illustrated comprises a top window pane 16 and a bottom pane 17. Secured to the opposing inside surfaces of the vertical jamb members 13 and 14 are the opposed vertical strips 18, 18, said vertical strips being formed with notches 19 at their upper portions to define respective seats for the side marginal portions of the upper window pane 16. As shown in Figure 2, the notches 19 extend vertically for approximately one-half the height of the respective vertical guide strips 18, 18, and are formed at their lower ends with upwardly facing notched portions 20, 20 in which the lower corner portions of the window pane 16 are receivable, the side marginal portions of the window pane being engaged against the vertical edges of the notches 19, 19. Secured to the opposing inside surfaces of the jamb members 13 and 14 are respective vertical filler strips 21, 21, which are engaged against the side marginal portions of the window pane 16 and which serve to fixedly secure the window pane in the notches 19, 19.

2

As shown in Figures 3 and 4, a horizontal stop strip 22 is secured to the bottom surface of the head jamb 12 between the top ends of the vertical guide strips 18, 18, the top marginal portion of the window pane 16 being engaged against the horizontal stop strip 22, and being secured thereagainst by a horizontal retaining strip 23 secured to the undersurface of head jamb 12 externally adjacent to the window pane 16.

The lower portions of the vertical guide strips 18 are provided with vertical forward edges 24 which are in alignment with the forward edges of the retaining strips 21, 21. The bottom window pane 17 is slidably engaged against the vertical forward edges 24, 24 of the guide strips 18, 18 and is retained thereagainst by additional vertical guide strips 25, 25 secured to the opposing inside surfaces of the vertical jamb members 13 and 14.

As shown in Figure 3, the window pane elements 16 and 17 overlap slightly at the intermediate portion of the window when the window pane elements are in their closed positions, and are slightly offset, the lower window pane member 17 being spaced from the upper window pane member 16 substantially by the horizontal width of the retaining strips 21, 21, as is clearly shown in Figures 3 and 4.

25 A tubular weather strip or filler member 26 of resilient deformable material is provided, said tubular member being engageable in the space between the lower marginal portion of the upper window pane and the upper marginal portion of the lower window pane, in the manner illustrated in Figure 3, to seal the space between the window panes when so desired. As shown in Figures 2 and 3, the weather strip member 26 is provided with a horizontal flange element 27 which is engageable on the top edge of the lower window pane member 17 to properly position the weather strip member and to insure proper support therefor. The flange 27 also provides a means for releasing the weather strip element 26 and removing same from between the window pane elements when so desired.

26 The forward vertical guide strips 25, 25 are formed at their upper portions with notches 28 opposing the notches 19 and defining spaces for receiving the side marginal portions of the lower window pane elements 17 and for storing said lower window pane element in an elevated position, as shown in dotted view in Figure 4.

27 As is clearly shown in Figures 3 and 4, the notches 28 are substantially triangular in shape, comprising the substantially horizontal edge portions 29 and the inclined, upwardly extending edge portions 30. The notches 28 are of sufficient vertical height to receive the side marginal portions of the lower window pane 17, as above explained, and to support the lower window pane in the slightly inclined position shown in dotted view in Figure 4, wherein the upper corner portions of the lower window pane rest against the top portions of the retaining strips 21, 21.

28 The guide strips 25 are formed adjacent the forward ends of the horizontal notch edges 29 with recesses 32 in which are pivoted respective hook members 33 which are engageable with the top edge of the lower window pane 17 when said window pane is in its closed position, as shown in Figure 3. The hooks 33 are employed to lock the lower window pane in closed position, and are accessible from inside the building in which the windows are installed, it being understood that the view of Figures 1 and 2 is taken from the inside of the building.

29 Secured to the inside surfaces of the guide strips 25, 25 are sealing strips 34, 34, said sealing strips including weather strip elements 35 of felt, or other suitable deformable sealing material, said elements 35 sealingly engaging the side marginal portions of the lower window pane 17.

30 In each of the window assemblies, one or both of the

vertical guide strips 25 may be formed with a horizontal slot 36 in which is slidably mounted a supporting bar 37, the bar 37 being slidable beneath the bottom edge of the window pane 17, when said window pane member is in elevated position, as shown in Figure 4, whereby to support the window pane element in said elevated position. As shown in Figure 3, the support bar 37 is disposed behind the sealing strip 34 and is retained thereby in the slot 36.

Obviously, only a single support bar 37 may be employed with each window assembly, the support bar being preferably provided in the vertical guide strip 25 associated with the center vertical jamb member 14, as shown in Figures 1 and 2.

The lower marginal portion of the bottom window pane member 17 has suitably cemented to the mid portion thereof a hand grip block 39, of plate glass, or the like, serving as a handle for raising and lowering the lower window pane member 17.

As above explained, the lower window pane member 17 may be at times stored in an elevated, out-of-the-way position, shown in dotted view in Figure 4, by engaging the side marginal portions thereof in the notches 28 of the vertical guide strips 25. Suitable screen members may be inserted in the window in place of the lower window pane member 17, the screen members being receivable in the positions formerly occupied by the lower window pane members 17.

When employed in its normal manner, the lower window pane member 17 may be locked in lowered position by means of the hook members 33, 33, as above described, and the space between the window pane members 16 and 17 may be sealed by employing a tubular horizontal weather strip member 26, as above explained. Under mild weather conditions, the window pane member 17 may be partially raised, as shown in Figure 4, and may be supported in elevated position by the locking bar 37, the locking bar being provided with an enlarged head portion 40 which protrudes from the slot 36, whereby the locking bar may be manually moved either to supporting position or to inoperative position. The window pane element 17 may be raised or lowered by means of its handle member 39, as above described.

The vertical guide strips 25 are preferably notched out at their top corner portions, as shown at 42, 42 to provide recesses for receiving the end portions of window shades, or for receiving window shade brackets for supporting the window shade end portions.

While a specific embodiment of an improved sashless window structure has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. A window structure comprising a rectangular window frame having vertical side members, a horizontal top member, and a horizontal sill member, respective first vertical guide strips secured to said side members, said guide strips being formed with notches at their upper portions to define respective seats, a first vertical window pane engaged against said guide strips and having its side marginal portions received in said seats, the lower portion of said strips having vertical forward edges, a second vertical window pane disposed adjacent said forward edges, respective filler strips secured to said side members and securing said first window pane in said seats, and respective additional vertical guide strips secured to said side members forwardly adjacent the side marginal portions of said second window pane, whereby said second window pane is vertically slideable between said forward edges and said additional vertical guide strips.

2. A window structure comprising a rectangular win-

dow frame having vertical side members, a horizontal top member, and a horizontal sill member, respective first vertical guide strips secured to said side members, said guide strips being formed with notches at their upper portions to define respective seats, a first vertical window pane engaged against said guide strips and having its side marginal portions received in said seats, the lower portions of said strips having vertical forward edges, a second vertical window pane disposed adjacent said forward edges, respective filler strips secured to said side members substantially in vertical alignment with said forward edges and securing said first window pane in said seat, respective additional vertical guide strips secured to said side members forwardly adjacent the side marginal portions of said second window pane, whereby said second window pane is vertically slideable between said forward edges and said additional vertical guide strips, and horizontally slideable means on the lower portion of at least one of said additional guide strips supportingly engageable at times beneath said second window pane.

3. A window structure comprising a rectangular window frame having vertical side members, a horizontal top member, and a horizontal sill member, respective first vertical guide strips secured to said side members, said guide strips being formed with notches at their upper portions to define respective seats, a first vertical window pane engaged against said guide strips and having its side marginal portions received in said seats, the lower portions of said strips having vertical forward edges, a second vertical window pane disposed adjacent said forward edges, respective retaining strips secured to said side members substantially in vertical alignment with said forward edges and securing said first window pane in said seat, respective additional vertical guide strips secured to said side members forwardly adjacent the side marginal portions of said second window pane, whereby said second window pane is vertically slideable between said forward edges and said additional vertical guide strips, and horizontally slideable means on the lower portion of at least one of said additional guide strips supportingly engageable at times beneath said second window pane, the upper portions of said additional guide strips being formed with notches facing said seats, said last-named notches being formed and arranged to at times receive the side marginal portions of said additional window pane and to support same in a fully elevated position.

4. A window structure comprising a rectangular window frame having vertical side members, a horizontal top member, and a horizontal sill member, respective first vertical guide strips secured to said side members, said guide strips being formed with notches at their upper portions to define respective seats, a first vertical window pane engaged against said guide strips and having its side marginal portions received in said seats, the lower portions of said strips having vertical forward edges, a second vertical window pane disposed adjacent said forward edges, respective retaining strips secured to said side members substantially in vertical alignment with said forward edges and securing said first window pane in said seats, respective additional vertical guide strips secured to said side members forwardly adjacent the side marginal portions of said second window pane, whereby said second window pane is vertically slideable between said forward edges and said additional vertical guide strips, horizontally slideable means on the lower portion of at least one of said additional guide strips supportingly engageable at times beneath said second window pane, the upper portions of said additional guide strips being formed with notches facing said seats, said last-named notches being formed and arranged to at times receive the side marginal portions of said additional window pane and to support the same in a fully elevated position, and hook means pivoted to the intermediate portions of said additional guide strips and formed and arranged to lockingly engage the top edge

of said second window pane when said second pane is in a fully lowered position.

5. A window structure comprising a rectangular window frame having vertical side members, a horizontal top member, and a horizontal sill member, respective first vertical guide strips secured to said side members, said guide strips being formed with notches at their upper portions to define respective seats, a first vertical window pane engaged against said guide strips and having its side marginal portions received in said seats, the lower portions of said strips having vertical forward edges, a second vertical window pane disposed adjacent said forward edges, respective vertical retaining strips secured to said side members substantially in vertical alignment with said forward edges and securing said first window pane in said seats, respective additional vertical guide strips secured to said side members forwardly adjacent the side marginal portions of said second window pane, whereby said second window pane is vertically slid able between said forward edges and said additional vertical guide

20

strips, horizontally slid able means on the lower portion of at least one of said additional guide strips supportingly engageable at times beneath said second window pane, the upper portions of said additional guide strips being formed with notches facing said seats, said last-named notches being formed and arranged to at times receive the side marginal portions of said additional window pane and to support same in a fully elevated position, a tubular silent weather strip element engageable between the lower marginal portion of said first window pane and the top marginal portion of said second window pane and being provided with a flange engaging on the top edge of said second pane, and hook means pivoted to the intermediate portions of said additional guide strips and formed and arranged to lockingly engage the top edge of said second window pane adjacent the ends of said flange when said second window pane is in a fully lowered position.
